COMBINATION SEAT AND WALL CABINET

Edward Harley Cawthon, Tampa, Fla.

Application May 15, 1951, Serial No. 15,188

Term of patent 3½ years

(Cl. D15—8)

To all whom it may concern:

Be it known that I, Edward Harley Cawthon, a citizen of the United States of America, residing at Tampa, in the county of Hillsborough, and State of Florida, have invented a new, original, and ornamental Design for a Combination Seat and Wall Cabinet, of which the following is a specification, reference being had to the accompanying drawing, forming part thereof.

In the drawing:

I claim:

The ornamental design for a combination seat and wall cabinet, as shown.

EDWARD HARLEY CAWTHON.
